TAP FOR CONTAINERS

Clive Selsey Phillips, London, England, assignor
to Phillips Telescopic Taps Limited, London,
England

Application April 23, 1932, Serial No. 607,177,
and in Great Britain August 5, 1931

30 Claims. (Cl. 221—21)

This invention is for improvements in or relating to taps for containers of the type in which an outlet member is normally arranged to extend within the container with the outer end of 5 the member located substantially flush with the outer wall of the container and to be partially withdrawn from the container to open the tap. An object of the invention is to provide an efficient tap of this character for use with highly 10 penetrating liquids of low viscosity.

According to this invention, a tap of the type described comprises a tubular outlet member, the outer end of which is closed and in the wall of which an outlet opening is provided arranged 15 normally to be covered, and a valve carried by said tubular member and arranged to control the said outlet opening and operable automatically to be actuated to open the outlet after the same is uncovered upon withdrawal of the 20 member from the container, the said valve being arranged to be moved automatically to close the said outlet upon an initial movement of the tubular member in the reverse direction to close the tap.

25 This construction of tap ensures a rapid cut-off for the flow of the liquid therethrough, whilst providing an extremely simple construction which is economical to produce.

The invention is more particularly described 30 hereinafter and defined in the appended claims.

In order that the invention may be fully understood, reference is directed to the accompanying drawing, in which:—

Figure 1 illustrates in side elevation a tap 35 constructed in accordance with the invention and showing the tap in the closed position.

Figure 2 is a view at right angles to Figure 1 illustrating the outer end of the tap.

Figure 3 is a section on the line 3—3 of Figure 2 and illustrating the tap in the open position.

Figure 4 is a section on the line 4—4 of Figure 3.

Figure 5 is a perspective detail view of a packing element illustrated in Figures 1 to 4, and

Figure 6 is a side elevation partly in section of a modified form of tap.

Referring to Figures 1 to 5 a tap is illustrated which comprises a hexagonal tube 1 mounted so as to be slidable in an axial direction within 50 an annular chamber in the form of a bush 2 disposed around the tube and carried by a supporting flanged member 3 to which it is secured by soldering at 4. The flanged member 3 is arranged to be secured to the wall of a wooden barrel and has holes 5 formed therein to permit

the flange to be screwed or riveted to the barrel with the interposition of a sealing washer 6. A tubular extension 3^a of the flange 3 is preferably tapered as illustrated to enable it to be made a tight fit within an opening in the barrel. 60 When used with metal containers the supporting flanged member is normally omitted and the tap is soldered direct to the container on the flange 12.

An aperture in the inner end 7 of the bush 2 65 through which the tube 1 extends is of a configuration conforming to the cross-section of the tube 1 and thereby prevents rotation of the tube relatively to the flange member 3.

Within the bush 2 a series of flexible annular 70 packing elements are mounted, each consisting of two flat rings of cork 8 cemented upon either side of a ring of fabric 9, Figures 3 and 5.

The inner configuration of the packing elements conforms to that of the tube 1 and the 75 elements are arranged to bear upon the outside of the tube with sealing contact. The packing elements are confined and sealed within the bush 2 by a ring member 10, Figure 3, which is pressed against the outermost element by a pair of diametrically opposed projections 11 formed upon an auxiliary flange 12 of the bush 2.

The outer end of the tube 1 is closed by a disc 13 and is provided with a cap 14 rotatably mounted upon the tube 1 and having a pair of diametrically opposed projections 15 arranged, when the tube is moved into the extreme inward position relatively to the container to pass through slots

16 in the auxiliary flange 12 and upon rotation of 80 the cap 14 the projections 15 engage with inclined surfaces 17 and force the flange of the cap towards the flange 12. A washer 18 is disposed between the cap and the flange 12 so that

when the cap is firmly secured in position it is 85 impossible for liquid to seep past the cap from the container. A bail 19 is mounted upon the cap 14 to facilitate the manipulation of the tap.

The lower wall of the tube 1 is provided with 90 an aperture 20, Figure 3, which, when the tube is located in its extreme inward position, is covered by the packing elements 8. A valve 21 is carried by a spring blade 22 secured within the tube 1 and is normally arranged to close the opening 20.

A relatively stiff wire member 23 is secured to the spring 22 and is provided with an extension 24 which is arranged, upon withdrawal 95 of the tube from the washer member 3, to abut against the rear end of the wall of the bush 2, so that a further withdrawal of the tube to its extreme outward position opens the valve and

100

105

110

permits fluid to flow through the tube and escape through the outlet opening 20. A notch 24^a is formed in the extension 24 which is arranged to engage beneath the edge of the end wall 7 and lock the valve in the open position as shown in Figure 3. Immediately the tube 1 is moved inwardly the notch 24^a is disengaged from the edge of the wall 7 and the valve 21 closes the opening 20 before it reaches the flange 12 and the wall of the container.

A perforated lug 25 is provided upon the flange 12 to enable the bail 19 to be wired and sealed thereto when necessary.

In the modified form of tap illustrated in Figure 15 the packing between the tube 1 and the bush 2 comprises a series of rubber, cork or similar washers 8^a with a metal ring 26 located between each pair of adjacent washers. The washers are arranged to contact with the outer surface of 20 the tube 1 similarly to the washers 8, 9 in the previous example, whilst the internal dimensions of the metal rings 26 are greater than the external dimensions of the tube, thus providing spaces between the internal 25 rings and the tube. Both this construction and that above described provide a flexibility in packing which ensures a minimum frictional contact between the washers and the tube, whilst the accurate contact between the washers and 30 the tube is maintained. In Figure 6 a hexagonal dished flange 3^b is provided in lieu of the flange 3 shown in Figure 1 and has a screwed ferrule 27 secured thereto to permit the tap to be screwed into a bush provided upon a container or a back 35 nut may be screwed on to the ferrule 27 interiorly of the container for the purpose of securing the tap thereto, and in this case the hexagonal flange 3^b may be arranged to be located within a hexagonal recess provided in the container and thereby enable the correct location of the outlet 40 opening 20 to be readily attained.

The non-rotatable mounting of the movable tube 1 of the tap ensures that the outlet opening 20 is always located in a downwardly directed 45 position which, particularly in the case of liquids of relatively low viscosity, is an important feature, as otherwise the liquid might be projected in a stream directed to one side or upwardly upon opening the tap, depending upon the position in 50 which the outlet opening happened to be. It will be appreciated that any other polygonal section of tube may be employed and that the tube may be circular in section and a pin and guide slot provided to prevent rotation thereof.

In a modification the sealing cap may be arranged to screw on to a screw-threaded ferrule provided upon the flange 3.

What I claim and desire to secure by Letters Patent is:—

60 1. A tap for fluids which comprises in combination a bush adapted for securing the tap to a container, a tubular outlet member extending through and slidably mounted in said bush, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member.

65 member in the opposite direction and before the outlet opening reaches said bush.

70 2. A tap for fluids which comprises in combination a single tubular outlet member slidably mounted in a bush adapted for securing the tap to a container, an outlet opening in said outlet member normally located within said bush, a valve normally closing said opening and means operable automatically to actuate said valve and open said outlet opening upon partial withdrawal of said tubular member from said bush only 75 after said opening has been moved beyond said bush and to close said opening during movement of the tubular member in the opposite direction and before the outlet opening reaches the bush.

80 3. A tap for fluids which comprises in combination a bush adapted for securing the tap to a container, a tubular outlet member extending through and slidably mounted in a non-rotatable manner in said bush, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.

85 100 4. A tap for fluids which comprises in combination a bush adapted for securing the tap to a container, packing in said bush, a tubular outlet member slidably mounted in said bush and extending through said packing, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.

105 110 5. A tap for fluids which comprises in combination a bush adapted for securing the tap to a container, packing in said bush, a tubular outlet member slidably mounted in said bush in a non-rotatable manner and extending through said packing, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.

115 120 6. A tap for fluids which comprises in combination a single tubular outlet member slidably

- member in the opposite direction and before the outlet opening reaches said bush.
21. A tap for fluids which comprises in combination a bush adapted for securing the tap to a container, packing in said bush consisting of a series of annular disc elements of flexible material sealed at their peripheries within said bush, a tubular outlet member polygonal in cross-section slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.
22. A tap for fluids which comprises in combination a bush adapted for securing the tap to a container, packing in said bush consisting of a series of annular disc elements of flexible material sealed at their peripheries within said bush, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a yieldingly controlled valve movably mounted on said outlet member and normally closing said outlet opening, an operative member on said valve arranged to abut against said bush to move the valve to open said outlet opening only after the same has been moved beyond said bush during the withdrawal of said outlet member and means operable to maintain said valve in the open position against said yielding control until said outlet member is initially moved to close the tap and said valve adapted to close the outlet opening before the same reaches the bush.
23. A tap for fluids which comprises in combination a bush adapted for securing the tap to a container, packing in said bush consisting of a series of annular disc elements of flexible material sealed at their peripheries within said bush, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening, means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.
24. A tap for fluids which comprises in combination a bush adapted for securing the tap to a container, packing in said bush consisting of a series of annular disc elements of flexible material sealed at their peripheries within said bush, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening, means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches the bush and rotatable means carried by said outlet member operable positively to lock and seal said member to said bush when the tap is closed.
25. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of said elements, a tubular outlet member slidably mounted in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches the bush and rotatable means carried by said outlet member operable positively to lock and seal said member to said bush when the tap is closed.
26. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of the said elements, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches the bush and rotatable means carried by said outlet member operable positively to lock and seal said member to said bush when the tap is closed.

matically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.

27. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of the said elements, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening and means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush.

28. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of the said elements, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a yieldingly controlled valve movably mounted on said outlet member and normally closing said outlet opening, an operative member on said valve arranged to abut against said bush to move the valve to open said outlet opening only after the same has been moved beyond said bush during the withdrawal of said outlet member and means operable to maintain said valve in the open position against said yielding control until said outlet member is initially moved to close the tap and said valve adapted to

close the outlet opening before the same reaches the bush.

29. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of the said elements, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening, means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches said bush, and means operable positively to lock and seal said outlet member to said bush when the tap is closed.

30. A tap for fluids which comprises in combination a bush adapted for securing the tap to a container, packing in said bush consisting of a series of annular disc elements of flexible material sealed at their peripheries within said bush and separated from one another by rings the internal diameter of which is greater than the internal diameter of the said elements, a tubular outlet member slidably mounted in a non-rotatable manner in said bush and extending through said packing and engaged frictionally around its circumference by each of said disc elements, said outlet member being closed at its outer end and provided with an outlet opening in the wall thereof which is covered by said bush when said outlet member is in the innermost position relatively to said bush, a valve carried by said outlet member and normally closing said outlet opening, means operable automatically to actuate said valve and open said outlet opening as the tubular member is withdrawn from the bush only after the outlet opening has been moved beyond the outer end thereof and to close said outlet opening during movement of the tubular member in the opposite direction and before the outlet opening reaches the bush and rotatable means carried by said outlet member operable positively to lock and seal said member to said bush when the tap is closed.

CLIVE SELSEY PHILLIPS.
